DESIGN FOR A DRESS ENSEMBLE

Carl H. Colcord, New York, N. Y.

Application December 11, 1937, Serial No. 73,524

Term of patent 3½ years

To all whom it may concern:

Be it known that I, Carl H. Colcord, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of an ensemble dress showing my new design.

Fig. 2 is a front view of the dress portion of the ensemble.

Fig. 3 is a rear view of Fig. 2.

Fig. 4 is a rear view of the jacket portion of the dress ensemble.

My design is characterized by the specific arrangement of the trimming on the jacket as shown.

I claim:

The ornamental design for a dress ensemble substantially as shown.

CARL H. COLCORD.
